[57] CLAIM

The ornamental design for an electrical connector with fluid cooling capability, as shown and described.

DESCRIPTION

FIG. 1 is an elevational view of one side of the electrical connector with fluid cooling capability forming my new design;

FIG. 2 is an elevational view of another side thereof;

FIG. 3 is an elevational view of one end thereof; and

FIG. 4 is an elevational view of the opposite end of the electrical connector with fluid cooling capability.

FIG. 4.

FIG. 2.

FIG. 1.

FIG. 3.
